LOWER JOURNAL FOR REVOLVING DOORS

Thurloe M. Hagenbook, Evansville, Ind., assignor to International Door Company, Evansville, Ind., a corporation of Illinois

Application December 11, 1936, Serial No. 115,431

15 Claims. (Cl. 20—18)

My invention relates broadly to revolving doors vertical sectional view taken through the lower journal of the revolving door and illustrating the journal in retracted position for permitting the shifting of the collapsed wings of the revolving door to one side of the revolving door drum or housing, certain of the parts being illustrated in side elevation; Fig. 3 is an enlarged cross sectional view of the lower end of the shaft structure of the revolving door and illustrating a portion of the retractable and projectable pintle in side elevation and showing the structure by which seepage of dust and dirt into the journal housing is obstructed; Fig. 4 is a transverse sectional view taken on line 4—4 of Fig. 1; Fig. 5 is a side elevational view partially broken away and illustrated in cross section and showing the projectable and retractable pintle employed in the construction of my invention; Fig. 6 is a vertical sectional view taken through the vertically shiftable control member by which movement is imparted to the pintle for effecting retraction or projection thereof; Fig. 7 is a vertical sectional view showing the cylindrical sleeve employed adjacent the base of the shaft of the revolving door in the construction of my invention; and Fig. 8 illustrates partially in side elevation and partially in cross section the internal concentric sleeve which surrounds the retractable and projectable pintle in the construction of my invention.

One of the objects of my invention is to provide a construction of lower journal for revolving doors in which the retraction and projection of the journaling means for the revolving door may be readily accomplished for allowing the revolving doors to be collapsed and shifted against the side of the drum or housing of the revolving door and readily restored to normal revolving position.

Another object of my invention is to provide a simplified construction of lower journal for revolving doors by which deleterious effects of dirt, grit and the like, upon the moving parts of the revolving door journal are substantially eliminated by constructing the lower journal in such manner that entry of dirt, grit and the like, is substantially obstructed.

A further object of my invention is to provide a simplified construction of self-oiling lower journal for the lower portion of a revolving door having means for enclosing the moving parts of the journal in a substantially dust and dirt tight housing for protecting the journal against seepage of dust, grit and the like.

A still further object of my invention is to provide a construction of retractable and projectible journal for revolving doors including an anti-friction thrust bearing adapted to receive the thrust of the hold-down spring.

Another object of my invention is to provide a simplified construction of anti-friction thrust bearing for journaling the lower portion of a revolving door in which the anti-friction thrust bearing is enclosed in a substantially dust and dirt tight housing adjacent the base of the central shaft of the revolving door while being free for retraction or projection for allowing the shifting of the collapsed revolving door wings to a position adjacent one side of the revolving door drum or housing or the journaling of the doors in revolving position.

Other and further objects of my invention reside in the construction of lower journal for revolving doors as set forth in the specification hereinafter following by reference to the accompanying drawing in which:

Figure 1 is a vertical sectional view taken through the lower journal of the revolving door with certain of the parts illustrated in side elevation and showing the journal in projected position for rotation of the revolving door wings within the revolving door housing; Fig. 2 is a

vertical sectional view taken through the lower journal of the revolving door and illustrating the journal in retracted position for permitting the shifting of the collapsed wings of the revolving door to one side of the revolving door drum or housing, certain of the parts being illustrated in side elevation; Fig. 3 is an enlarged cross sectional view of the lower end of the shaft structure of the revolving door and illustrating a portion of the retractable and projectable pintle in side elevation and showing the structure by which seepage of dust and dirt into the journal housing is obstructed; Fig. 4 is a transverse sectional view taken on line 4—4 of Fig. 1; Fig. 5 is a side elevational view partially broken away and illustrated in cross section and showing the projectable and retractable pintle employed in the construction of my invention; Fig. 6 is a vertical sectional view taken through the vertically shiftable control member by which movement is imparted to the pintle for effecting retraction or projection thereof; Fig. 7 is a vertical sectional view showing the cylindrical sleeve employed adjacent the base of the shaft of the revolving door in the construction of my invention; and Fig. 8 illustrates partially in side elevation and partially in cross section the internal concentric sleeve which surrounds the retractable and projectable pintle in the construction of my invention.

My invention is directed to a simplified construction of lower journal for revolving doors which is relatively inexpensive in production and which may be readily assembled. My invention provides for substantially enclosing the thrust bearing on which a revolving door is mounted and preventing the seeping of dust and grit into the thrust bearing by providing a serpentine obstructive path for the seepage of dust and grit to the bearing. A minimum number of parts are required for substantially enclosing the thrust bearing in a substantially dust and dirt tight housing, thereby rendering the structure of my invention simple and yet highly effective. It will be understood that the principles of my invention may be embodied in various forms and that details are not material. The present embodiment of the invention, therefore, is to be considered as merely indicative. The form illustrated in the drawing and hereinafter described in detail has been found to be one of the practical embodiments and capable of efficient operation and practical in construction.

Referring to the drawing in more detail, reference character 1 designates two of the oppo-

sitely projecting revolving door wings having their inner longitudinally extending edges substantially abutting the exterior wall of the housing 2. The housing 2 substantially encloses the tubular shaft 3 of the revolving door. The door has been foreshortened and a showing of the wing hangers omitted for purposes of simplification. A sleeve member 4 is provided in the lower end of the housing 2 and snugly fits therein for substantially preventing the entry of dust, dirt, grit and the like into the lower end of the housing 2. The sleeve member 4 is provided with a shoulder 5 adjacent its upper extremity. The upper end of the sleeve member 4 is provided with an aperture or reduced section which is internally screw threaded as indicated at 6. The lower end of sleeve member 4 is recessed to provide an internal annular seat or shoulder 7. The recess in the end of sleeve member 4 is internally screw threaded as indicated at 8. The tubular central shaft 3 is provided with screw threads 9 on the end thereof, adapted to engage the internal screw threads 6 in the upper end of sleeve member 4.

An internal concentric sleeve 10 is disposed within sleeve member 4 on the pintle 20, which is slidably and non-rotatively movable with respect thereto. The internal concentric sleeve 10 has an annular flange 11 thereon which engages over the lower end of a bushing 14. Bushing 14 serves as a packing means between sleeve member 4 and internal concentric sleeve 10 and is constructed from self-oiling bronze.

The recessed end of the sleeve member 4 is adapted to receive the self-oiling bronze disc washer 15 and the gasket 16 in super-imposed relation as shown more particularly in Fig. 3. The gasket 16 is provided with a central thickened portion 16a serving as a seal with respect to the cylindrical walls of the pintle 20. The pintle 20 has a longitudinally extending keyway 20a therein adapted to be aligned with a corresponding keyway 10a in the internal concentric sleeve 10 for receiving the key 21 by which a positive lock is provided between the pintle 20 and the internal concentric sleeve 10 while allowing retraction or projection of the pintle 20.

The self-oiling bronze disc washer 15 and gasket 16 are retained in position by means of the screw threaded end plate 17. The end plate 17 has external screw threads 18 thereon adapted to engage the internal screw threads 8 in the recess in the end of sleeve member 4. Sockets 19 are provided in the lower face of end plate 17 for facilitating the insertion or removal of end plate 17. The end plate 17 has a central chamfered portion 17a adapted to receive the central thickened portion 16a of gasket 16 for insuring a relatively tight seal around pintle 20 and obstructing the seepage of dirt, dust, grit and the like toward the housing which encloses the thrust bearing.

It will be noted that the flange 11 on the concentric sleeve has an outer diameter substantially less than the inner diameter of the sleeve member 4, and that the length of the internal sleeve 10 is substantially shorter than the length of the smooth inner bore of the sleeve member 4, so that the sleeve 10 will not bind in the sleeve member 4 or against shaft 3, upon the tightening of end plate 17. On the contrary, the sleeve member 4 is free to rotate with respect to the sleeve 10 with a minimum of wear because of the self-oiling bushings 14 and 15 which constitute rotary and end bearing members, respec-

tively. Dirt, grit, etc., are prevented from entering these bearing members primarily by the packing washer or gasket 16, and also by reason of the serpentine path through the end and rotary bearings and around the flange 11. This lower bearing assembly in combination with an upper sleeve bearing 36, hereinafter more fully described, serves to stabilize the operation of the revolving door about the pintle 20, with a minimum of wear in the bearings due to the provisions of my invention, and with resulting long life for the bearings.

The lower end of pintle 20 is provided with a frusto-conical terminus which is slotted as indicated at 22 allowing the terminus to be received in the frusto-conical seat 23 which is suitably supported in the base or floor over which the revolving door operates. A diametrically extending member 23a serves as a means for retaining the pintle in a fixed position when the pintle is lowered into the seat 23.

The upper end of pintle 20 is provided with an extension 24 of reduced section having a screw threaded recess 25 in the upper end thereof for receiving the end of the headed screw 26 which extends through the internal cylindrical recess 27 in coupling member 28 and through the bore 29 extending therefrom; through upper thrust bearing ball race plate 30 through the lower thrust bearing ball race plate 31 and into the screw threaded socket 25 in the upper end of the extension 24 on pintle 20. The headed screw threaded stud 26 serves as a connecting means between coupling member 28 and the extension 24 of pintle 20 for allowing a longitudinal force imparted through coupling member 28 to be communicated to pintle 20 so that pintle 20 may be projected or retracted while the door is free to revolve. I provide a set of ball bearings 32 between the upper and lower thrust bearing ball bearing race plates 30 and 31. The ball bearings 32 provide an anti-friction surface against which the thrust of spring 42 is effective.

The coupling member 28 has the cylindrically recessed end thereof arranged to receive the end of the link member 33 which extends longitudinally through the tubular central shaft 3. The juncture formed by the entry of link 33 into the cylindrically recessed end of coupling member 28 provides a shoulder 34 on which gasket member 35 is arranged to seat. Gasket member 35 has an inner bore fitting snugly with respect to the external cylindrical surface of link 33. The external cylindrical periphery of the gasket 35 conforms snugly with the internal diameter of tubular central shaft 3. The lowermost limit of gasket 35 is the shoulder 34 formed by the juncture of coupling member 28 and link member 33. The gasket 35 substantially obstructs the passage of dust, dirt, or other deleterious matter downwardly and into the housing within which the thrust bearing is confined. As has already been explained, dust, dirt, foreign matter, and other deleterious material is prevented from reaching the thrust bearing from below because of the serpentine passage through which such matter would have to pass because of the construction of the journal at the base of the revolving door. To further guard against the seepage of dust, dirt or other deleterious matter into the thrust bearing, I provide a cylindrical sleeve 36 constructed from self-oiling bronze and secured to the extension 24 of the pintle 20 and disposed within the tubular central shaft 3 in a position

normally just below the ball races which confine the ball bearings 32. When the pintle 20 is in retracted position the sleeve 36 moves with the pintle substantially protecting the thrust bearing 3 within its enclosure as heretofore described. As the link 33 is shifted upwardly, gasket 35 is correspondingly moved as the outer cylindrical periphery of gasket 35 is free to slide with respect to the inner wall of the tubular central shaft 3 thus protecting the thrust bearing within its housing as described.

The lower end of link 33 is secured in the upper end of the cylindrical recess 27 in coupling member 28 by suitable means such as diametrically extending rivet or pin 37. The upper end of link 33 fits into cylindrical socket 38 in the lower portion of vertically shiftable or slidable member 39. The socket is provided with elongated slots 40 in diametrically opposite positions in the side walls of the recessed portion 38. A transversely extending pin 41, secured in the upper end of link 33 passes through the slots 40 thus preventing relative rotation between link member 33 and slidable member 39 while allowing a limited amount of lost motion between the link 33 and the slidable member 39. A coil spring 42 is mounted in recess 38 and is effective against the upper end of link member 33 for normally holding the end 22 of pintle 20 in socket 23 in the foundation or base support for the revolving door.

The shiftable or slidable member 39 is provided with means for locking the shiftable member in either of two limiting positions. The slidable or shiftable member 39 is provided adjacent its upper extremity with a laterally extending cylindrical recess 43 adapted to receive a sleeve member or liner 44 within which coil spring 45 is operative to normally eject detent 46 having a head 40 and flange 47 thereon by which either aperture 48 or 49 in cylindrical housing 2 may be engaged for locking slidable member 39 in either of two positions. The spring operated detent is provided with an oil passage extending into the housing which surrounds the detent as indicated at 50. The sleeve 44 projects from the side of slidable member 39 and through the longitudinally extending slot 51 in one wall of the tubular central shaft 3 as shown. The shiftable member 39 is also provided with a finger grip 52 which is relatively narrow in section and which extends through slot 51 in the tubular central shaft 3 and also through the slot 53 in the housing 2 so that the finger grip 52 is free to be shifted vertically within such limits as will permit the retraction or projection of the pintle. The finger grip 52 is secured to the shiftable member 39 in any desired manner such as by way of screw member 54 which passes through the aperture 55 in the shiftable member 39.

Thus it will be seen that manipulation of the finger grip 52 in an upward direction serves to retract pintle 20 because transverse pin 41 of link 33 is engaged in the end limits of slots 40 and the force communicated through link 33 to coupling member 28 and through the headed screw threaded stud 26 to the upper extension 24 of pintle 20, allowing the pintle to be retracted in the position illustrated in Fig. 2 and the revolving door wings collapsed and the collapsed door moved to one side of the door drum or housing. The pintle is latched at the retracted position by the engagement of the end detent 46 in aperture 48. When the revolving door wings have been restored to the central position within

the door drum or housing, pintle 20 is ready to be projected and can be projected by downward movement of finger grip 52 and the shifting of detent 46 into aperture 49, the force being communicated through link 33, coupling member 28, 5 stud 26 to the upper extension 24 of the pintle to the lower end 20 of the pintle. Sufficient lost motion is provided to allow proper adjustment of the headed end of stud 26 in cylindrical recess 27 in the upper end of coupling member 28. The 10 retraction and projection steps heretofore explained are carried out while a relatively tight seal is maintained at all times in the lower end of the journal as heretofore described in connection with Fig. 3. The self-oiling characteristics of the sleeve 36, bushing 14 and washer 15 are such that lubrication of the lower journal becomes unnecessary. The serpentine path to the thrust bearing is such that dust, dirt and foreign matter is substantially excluded from the 20 bearing and long useful life of the bearing assured.

While I have described my invention in one of its preferred embodiments, I desire that it be understood that modifications may be made and that no limitations upon my invention are intended other than may be imposed by the scope of the appended claims.

What I claim as new and desire to secure by Letters Patent of the United States is as follows: 30

1. Mounting means for revolving doors comprising in combination with a tubular shaft, a projectible and retractible pintle in the end of said tubular shaft, a thrust bearing for rotatably journaling the revolving doors with respect to the 35 pintle, and a labyrinth packing device mounted on the said end of said shaft and surrounding said pintle for preventing the seepage of dust, grit and the like into said thrust bearing.

2. Mounting means for revolving doors comprising in combination with a tubular shaft, a projectible and retractible pintle in the end of said tubular shaft, a thrust bearing for rotatably journaling the revolving doors with respect to the 40 pintle, and a set of concentric sleeve members 45 disposed between said shaft and said pintle and having the outermost one thereof fixed to said shaft and the innermost one surrounding said pintle, the said sleeve members being interfitted to prevent direct entry of dust, grit and the like 50 into the thrust bearing except through a serpentine path.

3. Mounting means for revolving doors comprising in combination with a tubular shaft, a control shaft extending through said tubular 55 shaft, a pintle longitudinally shiftable within said tubular shaft, a thrust bearing disposed between said control shaft and said pintle, and means for substantially enclosing said thrust bearing within a portion of the tubular shaft, comprising packing means between said control shaft and said tubular shaft and a multiplicity of telescopically arranged sleeve members disposed between said tubular shaft and said pintle and having the outermost one thereof fixed to said shaft and the 65 innermost one surrounding said pintle, the said sleeve members being interfitted to obstruct entry of dust, grit and the like into the thrust bearing while allowing projection and retraction of said pintle. 70

4. Mounting means for revolving doors comprising in combination with a tubular shaft, a control shaft extending through said tubular shaft, a pintle projectible and retractible through the end of said tubular shaft, a thrust bearing 75

disposed between said pintle and said control shaft, and means carried by said tubular shaft and establishing frictional inter-connection with the exterior wall of said pintle, said means comprising a multiplicity of concentrically arranged sleeve members operating to obstruct the direct entry of dust, dirt, grit and the like into the thrust bearing.

5. Mounting means for revolving doors comprising in combination with a tubular shaft, a pintle projectible and retractible through the end of said tubular shaft, a control member shiftable to either of two limiting positions through said tubular shaft, a thrust bearing disposed between 10 said control member and the upper end of said pintle, a gasket member disposed about said control member and fitting slidably within said tubular shaft, and means carried by the end of said tubular shaft and operating as a seal with respect to said pintle, said gasket and said means 15 substantially preventing the seepage of dust into said thrust bearing.

6. Mounting means for revolving doors comprising in combination with a tubular shaft, a 20 pintle projectible and retractible through the end of said tubular shaft, a control member shiftable to either of two limiting positions through said tubular shaft, a thrust bearing disposed between 25 said control member and the upper end of said pintle, a gasket member disposed about said control member and fitting slidably within said tubular shaft, a cylindrical sleeve member carried by the end of said tubular shaft, a plurality of concentric bushings disposed within said sleeve member, one of said bushings being slidably and non-rotatively mounted with respect to said pintle, and means 30 engaging the end of said sleeve member for maintaining said bushings in position with respect to said pintle, whereby said thrust bearing is substantially protected against the entry 35 of dust while allowing said pintle to be projected and retracted.

7. Mounting means for revolving doors comprising in combination with a tubular shaft, a 40 tubular housing concentrically disposed about said shaft, a pintle projectible and retractible through the end of said tubular shaft, a control member shiftable to either of two limiting positions through said tubular shaft, a thrust bearing disposed between 45 said control member and the upper end of said pintle, a gasket member disposed about said control member and fitting slidably within said tubular shaft, a cylindrical sleeve member carried by the end of said tubular shaft and having an outer diameter equal to the inner 50 diameter of said tubular housing, a multiplicity of concentrically disposed bushings within said sleeve member, means for keying one of said bushings with respect to said pintle for allowing 55 projection or retraction of said pintle in a predetermined vertical plane, and means secured in the end of said sleeve member for confining said bushings within said sleeve member.

8. Mounting means for revolving doors comprising in combination with a tubular shaft, a 60 tubular housing concentrically disposed about said shaft, a pintle projectible and retractible through the end of said tubular shaft, a control member shiftable to either of two limiting positions through said tubular shaft, a thrust bearing disposed between 65 said control member and the upper end of said pintle, a gasket member disposed about said control member and fitting slidably within said tubular shaft, a cylindrical sleeve member carried by the end of said tubular shaft

and having an outer diameter equal to the inner diameter of said tubular housing, a multiplicity of concentrically disposed bushings within said sleeve member, means for keying one of said bushings with respect to said pintle for allowing 5 projection or retraction of said pintle in a predetermined vertical plane, and means for confining said bushings within said sleeve member, said last mentioned means including a sealing gasket establishing an annular sealing zone about said 10 pintle.

9. A lower journal for revolving doors comprising in combination with a tubular shaft, a pintle projectible and retractible through the end of the tubular shaft, a sleeve carried adjacent to 15 the upper end of said pintle and slidable within the cylindrical walls of said tubular shaft, and a self-oiling bushing mounted on the said end of said shaft and engaged with said pintle for journaling said tubular shaft with respect to the lower 20 end of said pintle.

10. A lower journal for revolving doors comprising in combination with a tubular shaft, a tubular housing concentrically disposed about 25 said shaft, a pintle projectible and retractible through the end of said tubular shaft, said pintle having an upper portion of reduced section, a self-oiling sleeve carried by the reduced section of said pintle and slidable interiorly of said tubular shaft, and a plurality of concentrically disposed sleeve members mounted adjacent the lower 30 end of said tubular shaft and filling the space between said tubular shaft and said tubular housing and surrounding the projectible and retractible pintle, the outermost of one of said sleeve 35 members being carried by said shaft and rotatable with respect to said pintle.

11. A lower journal for revolving doors comprising in combination with a tubular shaft, a pintle projectible and retractible through the end 40 of said shaft, a cylindrical sleeve member carried by the end of said shaft, a plurality of concentric bushings disposed within said sleeve member, one of said bushings being slidably and non-rotatively mounted with respect to said pintle, and means 45 engaging the end of said sleeve member for maintaining said bushings in position.

12. A lower journal for revolving doors as set forth in claim 11 and wherein said means includes a sealing gasket establishing an annular sealing zone about said pintle.

13. A lower journal for revolving doors as set forth in claim 11, and wherein said means includes a self-oiling disc washer disposed in abutment with at least the bushing which is non-rotatively mounted with respect to said pintle.

14. A lower journal for revolving doors as set forth in claim 11, and wherein another of said plurality of bushings constitutes a self-oiling bearing member for facilitating rotary movement 60 of said shaft with respect to said pintle.

15. A lower journal for revolving doors comprising in combination with a shaft, a pintle, a cylindrical sleeve member carried by said shaft, a bushing having a flange thereon at its lower end 65 slidably and non-rotatively mounted with respect to said pintle, a self-oiling cylindrical bushing disposed between said sleeve member and the aforesaid bushing above the said flange thereon, a self-oiling disc washer carried by said pintle beneath said flange, and means carried by said sleeve member for supporting said washer and said bushings in position.
